BOTTLE CASE

Albert Dale Erickson, Des Moines, Iowa, assignor
to C. E. Erickson Company, Inc., Des Moines,
Iowa, a corporation of Iowa

Application August 4, 1951, Serial No. 16,156

Term of patent 14 years

(Cl. D58—12)

To all whom it may concern:

Be it known that I, Albert Dale Erickson, a citizen of the United States, and a resident of Des Moines, in the county of Polk and State of Iowa, have invented a new, original, and ornamental Design for a Bottle Case, of which the following is a specification, reference being had to the accompanying drawing, forming a part thereof.

Figure 1 is a perspective view of a bottle case embodying my new design;

Figure 2 is a top plan view thereof; and
Figure 3 is an end elevational view thereof.

I claim:

The ornamental design for a bottle case, substantially as shown.

ALBERT DALE ERICKSON.
